UNITED STATES PATENT OFFICE

2,622,861

ROTARY HEARTH FURNACE

Randal E. Talley, Irwin, Pa.

Application March 8, 1950, Serial No. 148,457

8 Claims. (Cl. 263—7)

1

This invention relates to improvements in industrial heating equipment, more particularly to rotary hearth heating furnaces with automatic means for charging and discharging the products to be heated. Automatic charging and discharging of rotary furnaces was first disclosed in Patent No. 1,783,156, granted to me November 25, 1930.

For the purpose of clarity, the invention is illustrated and described as applied for heating steel billets prior to piercing and rolling into seamless steel tubing. This is merely one of the large number of industrial heating processes to which the invention may be applied.

The major components of the present invention comprise in combination, a rotary hearth furnace, a charging machine, a discharge machine and an adjustable sequence controller for coordinating the hearth movements with the charging and discharging mechanisms.

In the manufacture of seamless tubing it is essential that the mill be capable of producing the wide variety of sizes of tubing of varying lengths and wall thickness required by the trade. The billets from which the tubes are made likewise vary in size and weight.

In passage through the rotary hearth furnace, the larger billets require more hearth space than do the smaller billets. To permit efficient loading of the hearth, it is therefore essential to coordinate the movement of the hearth with the charging and discharging operations so as to permit the various sizes of billets to be loaded on the closest permissible hearth spacing. To meet this condition, the hearth drive is arranged to move the hearth progressively forward in a step by step movement, the size of the "step" being adjustable to suit the loading requirements of the various sizes of billets.

The matter of loading efficiency is also burdened by the fact that the change from one size billet to another occurs at frequent intervals. Oftentimes the run on a given size billet is not sufficient to fill the furnace. To completely empty the furnace and make a fresh start at each change in the hearth spacing is not commercially feasible because the flow of billets to the piercing mill would be interrupted for an extended period between each run. To maintain continuity of operation during such transitory periods, the charging of billets on the new hearth spacing must begin immediately upon completion of the charging of billets at the old hearth spacing, and during the period required for filling the furnace with the new run or runs, the discharger

2

must continue to function on the old hearth spacing until the previous run is exhausted. To achieve this result the movements of the charger, discharger and hearth are coordinated through 5 the sequence controller so that in effect the hearth moves forward in steps of one size for loading and steps of a different size for unloading, while the charger functions in proper sequence with the loading movement of the hearth and the discharger in proper sequence with the unloading movement.

A still further complication arises from the fact that the furnace unit must operate at high speed to keep pace with the piercing mill. Numerous 10 sizes of tubes are produced at a rate of 300 tubes per hour. To keep pace with this rate of production, the furnace unit must deliver a hot billet every twelve seconds. During this twelve second interval the charging machine must complete 15 the cycle of movements required for placing a cold billet in the furnace, the discharge machine must complete a similar cycle of movements in substantially reverse order to remove a hot billet from the furnace, and the furnace hearth must 20 move forward in the required index to match the loading and unloading operations.

The mass of the moving parts is of such magnitude that it is physically impossible to attain 25 operating speeds high enough to permit the required movements to follow one after the other. For example, the moving portion of the charging 30 machine weighs approximately 30,000 pounds and to place a cold billet in the furnace its forward and back travel approximates twenty feet in each direction. The weight and travel of the discharge machine is substantially the same. The rotating hearth of the furnace weighs approximately 1,150,000 pounds and its station to 35 station travel, measured at its periphery, may vary from a minimum of eight inches to a maximum of four feet.

Under the foregoing conditions, and with particular reference to mass, time and distance, it will be immediately apparent to those skilled in the art that the required sequence of movements can be consummated in the available time interval only by the development of novel means to supplement commercially available apparatus and controls.

40 In the accompanying drawings constituting a part hereof, and in which like reference characters designate like parts:

Fig. 2 a similar view of a sequence controller;
Fig. 3 is a side elevational view of the sequence controller taken along the line 3—3, Fig. 2;

Fig. 4 is a side elevational view of the sequence controller taken along the line 4—4, Fig. 2;

Fig. 5 is a sectional elevational view of the charging machine and a portion of the rotary furnace;

Fig. 6 is a sectional elevational view of a portion of the furnace and hearth drive mechanism;

Fig. 7 is a sectional elevational view of the discharge machine and a portion of the rotary furnace;

Fig. 8 is a schematic wiring diagram illustrating a control circuit;

Fig. 9 is a view similar to Fig. 1, showing a different pattern of hearth loading; and

Fig. 10 is a plan view diagrammatically illustrating the sequence controller of Fig. 2 in a different operating position.

Referring to Fig. 1 of the drawings, the rotary hearth furnace is generally designated by the numeral 1, the charging machine by the numeral 2, the discharge machine by the numeral 3 and the adjustable sequence controller by the numeral 4.

The hearth of the rotary furnace is driven by electric motor 5 through differential gear unit 6, the power from which is transmitted through shafts 7 and 7' and chain drives 8 and 8' to reducers 9 and 9', and thence to bevel pinions 10 and 10' which engage bevel gear 11 attached to the under side of the rotary hearth. Hearth drive motor 5 is equipped with solenoid brake 5a to permit quick and accurate stopping of the hearth. The two bevel pinions 10 and 10' are located diametrically opposite each other and are powered through the differential drive unit 6 to the end that the circumferential thrust required for rotating the hearth is applied equally at two points spaced at 180 degrees and all side thrust thereby eliminated. Further details of the hearth construction and the means employed for its rotatable mounting are shown in Fig. 6. The vertical support of the hearth is provided by a plurality of rollers 12 and 12' carried on journal bearings 13 which are circumferentially mounted on the furnace foundation in two or more concentric rows. The treads of rollers 12 and 12' engage circular tracks 14 and 14' attached to the underside of the hearth structure. True rolling contact across the tread face of rollers 12 and 12' is attained by tapering the tread and mounting journal bearings 13 with an outward cant so that the axis of the rollers intersects the vertical axis of the hearth at track level.

The concentric movement of the hearth in respect to its vertical axis is maintained by means of rollers 15 carried on journal bearings 16 which are circumferentially mounted on the furnace foundation concentric with the vertical axis of the hearth. The tread face of rollers 15 engage track 17 which is attached to the inner circumference of the hearth structure.

To function properly in the manner disclosed, it is essential that the rotating hearth remain flat and concentric. To this end, the main body portion of the supporting steelwork 18 is made strong and rigid with a comparatively weak section of spacer steel 19 mounted above it to support the refractory hearth deck. The spacer steel is loosely mounted to permit free

4

expansion in all directions and is also vented laterally to permit free circulation of the surrounding air. Supporting steelwork 18 is thus freed of the distortive temperature difference normally encountered in conventional hearth structures with the refractory deck mounted directly on the upper face of the main supporting steelwork.

The flatness and concentricity of the hearth structure is further augmented by circular curb members 20 and 20' which provide lateral curb support for the refractory hearth deck. These two members comprise an integral part of the main hearth support 18. There is no fixed mechanical connection between them and spacer steel 19. The upper portion of curb members 20 and 20' consists of an annular steel trough which is filled with water and in cooperation with dependent annular flanges 21 and 21' serve to seal the clearance gaps 22 and 22' between the moving hearth and the stationary side walls of the furnace. The water filled annular troughs thus serve the dual purpose of sealing the furnace and providing a strong water cooled structure for holding the hearth flat and concentric.

The lower portion of the furnace side walls in immediate proximity to the rotating hearth deck is made up of wedge shaped tile 23 and 23' circumferentially mounted on similar shaped castings 24 and 24'. Both of these members are exteriorly accessible for replacement or repair without cooling off or shutting down the furnace.

The horizontal clearance gaps 22 and 22' between the furnace side walls and the rotating hearth are adjustable as to height by means of jackscrews 25 which are built into the foot supports of the annular steel structure which encompasses the brickwork of the heating chamber. These jackscrews also serve to re-level the furnace in the event of unequal settling of the foundations.

Referring to Fig. 5 showing the charging machine, wheel mounted carriage 26 is arranged to move horizontally forward and back on track 27, the path of movement being in line with the radial centerline of the charging door of the rotary hearth furnace 1. The carriage is driven by electric motor 28 equipped with solenoid brake 28a to permit quick and accurate control of the stopping positions of the carriage. Power from motor 28 is transmitted through speed reducer 29 to gear 30 which engages rack 31 attached to the carriage. Underslung boom 32 is mounted on the understructure of carriage 26 by means of bell cranks 33 and 33' and slideable collars 34 and 34'. The bell cranks are supported at their fulcrum point by journal bearings 35 and 35' attached to the understructure of the carriage. The load carrying arms of the bell cranks engage the slideable collars through journal bearings 36 and 36'. The driven arms of the bell cranks are tied together for movement in unison by connecting rod 37 and journal bearings 38 and 38'. The boom mounting as described provides a pantograph suspension for raising and lowering boom 32 by imparting horizontal movement to connecting rod 37 and to those skilled in the art it is known that the boom remains horizontal during its up and down movement. Power is imparted to connecting rod 37 by means of hydraulic cylinder 39. The body of the hydraulic cylinder is pivotally attached to boom carriage 26 by means of mounting bracket 40, and its piston rod 39a is pivotally

attached to connecting rod 37 by means of anchor bracket 41.

Boom 32 is provided with clamping jaws 32a and 32b arranged to clamp the billets endwise for charging them into the furnace. With this arrangement of the jaws, the billets may be loaded close together on the hearth with resultant improvement in furnace efficiency and output as compared to the results obtainable from conventional boom jaws arranged to clamp the billets crosswise and therefore requiring a wider spacing of the billets on the hearth to permit the crosswise clamping jaws to function.

Jaw 32a is attached in fixed position at the inner end of the boom. Jaw 32b is slidably mounted on the boom and powered for opening and closing by hydraulic cylinder 42. The body of the hydraulic cylinder is attached to slideable collar 34' and its piston rod 42a is attached to movable jaw 32b. The general construction and operation of the boom and its jaws is the same as a monkey wrench with powered means for opening and closing the movable jaw.

Adjustment of the jaw opening to suit the varying lengths of billets is obtained by means of adjusting screw 43 which is rotatably mounted on boom 32 by means of radial thrust bearings 44 and 44'. The adjusting screw is driven by means of electric motor 45 in conjunction with speed reducer 46, both of which are mounted on the outer end of boom 32. The reactive thrust for shifting the position of boom 32 in respect to slideable support collars 34 and 34', and movable jaw 32b, is supplied by chaser nut 47 in threaded engagement with adjusting screw 43 and non-rotatably mounted in thrust housing 48 which is attached to slideable collar 34'.

The mechanical construction of the discharge machine, Fig. 7, is identical to the charging machine as previously described. Its wheel mounted carriage 49 is arranged to move horizontally forward and back on track 50, the path of movement being in line with the radial centerline of the discharge door of rotary hearth furnace 1.

The functional design of adjustable sequence controller 4 is shown in sectional plan view Fig. 2, and sectional elevational views Fig. 3 and Fig. 4.

The component parts of the adjustable sequence controller are mounted in steel housing 72 which is provided with hinged covers 72a and 72b to permit ready accessibility for sequence adjustments. The major functional components of the sequence controller consist of cam cylinders 73 and 74 and their respective engaging pawls 75 and 76.

Cam cylinder 73 controls the hearth spacing of billets being charged into the furnace and is comprised of a plurality of notched cam discs 73a, 73b, 73c, etc. secured to shaft 77 which is rotatably mounted in journal bearings 78 and 78'. The number of notches in the cam discs is varied progressively to provide a suitable range of hearth spacings for the various sizes of billets. For example, cam disc 73a may have two notches to provide a hearth spacing of 48 inches; cam disc 73b—three notches for 32" hearth spacing, cam disc 73c—four notches for 24" hearth spacing, and so on up to cam disc 73k with twelve notches for 8" hearth spacing. Cam cylinder 74 functions in keeping with the hearth spacing of billets being discharged from the furnace and is comprised of a plurality of notched cam discs 74a, 74b, 74c, etc., secured to shaft 79 which is rotatably mounted in journal bearings 80 and 80'.

Cam cylinder 74 is identical to cam cylinder 73

except that the cam discs are mounted for rotation in the opposite direction.

Cam cylinder 73 is powered through countershaft 81 which is rotatably mounted in journal bearings 82 and 82' and connected to the slow speed shaft of hearth drive speed reducer 9' by flexible coupling 83. Gear 84 mounted on countershaft 81 engages gear 85 attached to cam cylinder 73 and thus rotates it proportionately to the movement of the furnace hearth. Cam cylinder 74 is driven by gear 85 of cam cylinder 73 which engages gear 86 attached to cam cylinder 74. Gears 85 and 86 are identical in size, therefore cam cylinders 73 and 74 rotate at like speeds but in opposite directions.

Pawl 75 is adjustably mounted on pawl shaft 87 and by means of pawl index pin 75a may be positioned to engage any desired cam disc of cam cylinder 73. Pawl 76 is similarly mounted on pawl shaft 89 and by means of pawl index pin 76a may be positioned to engage any desired cam disc of cam cylinder 74. The pawl shafts are mounted for oscillating movement in bearings 88, 88', 90 and 90' and are spring loaded to insure positive engagement between pawl and cam by means of leaf springs 91 and 92. Tension on the pawl springs is adjustable by means of adjusting screws 93 and 94.

Normally closed switch 97 is mounted on housing 72 in operative engagement with actuator lever 95 which is secured to pawl shaft 87. When pawl 75 drops into a notch of the engaging cam disc, actuator lever 95 is depressed and normally closed contact 97a through switch 97 is thereby interrupted. Normally closed switch 98 is similarly mounted and operated by means of actuator lever 96 mounted on pawl shaft 89.

The manner in which the adjustable sequence controller functions in cooperation with auxiliary controls to attain the stated objects of the invention is disclosed in full detail by the following description of the movements involved and the means employed for producing them. For purposes of clarity the various movements are described as occurring separately. In actual practice, numerous movements occur simultaneously and others substantially overlap. The electrical control devices employed for this purpose, together with their connecting circuits, are diagrammatically portrayed by schematic wiring diagrams, Fig. 8.

The rate at which billets are discharged from the furnace is controlled by electric time clock 99, the timing interval of which is adjustable to suit the permissible rate of production on billets of various sizes. Confirmation push-button 100 is a safety switch under manual control of the piercing mill operator. Its function is to prevent automatic delivery of a hot billet by the time clock before the piercing mill is ready to receive it. When the piercing mill is in readiness to receive a hot billet, the operator momentarily closes contact 100a to arm the time control circuit. This normally occurs prior to the expiration of the timing interval of the time clock but it may occur later with the same ultimate result. In normal operation the operator arms the time control circuit and the time clock completes it. In case of mill delay the time control circuit is armed by the time clock and completed by the operator.

The momentary closing of contact 100a energizes relay coil 142 and closes contact 142a which serves as an interlock to maintain the circuit through coil 142 after contact 100a is opened.

At the expiration of the interval for which the time clock is set, clock contact 99a closes and clock contact 99b opens. The closing of contact 99a lights red signal light 146 to indicate that a hot billet is to be delivered. The opening of contact 99b de-energizes relay coil 144, opening contact 144a and closing contact 144b. The opening of contact 144a extinguishes green signal light 145 which burns during the timing interval. The closing of contact 144b energizes relay coil 143 and closes contact 143a, thus energizing "forward" starting coil 106 of motor 51 and setting discharge carrier 49 in motion toward the furnace.

The energizing of starter coil 106 closes interlock contacts 106a and 106b, and opens interlock contacts 106c, 106d and 106e. The opening of contact 106c disarms "reverse" starter coil 109 for purposes of safety. The opening of contact 106d disarms the holding circuit of "hearth starting" relay coil 137. The opening of contact 106e de-energizes relay coils 142 and 143, to open contacts 142a and 143a. The opening of contact 142a disarms the holding circuit of relay coil 143. The opening of contact 143a disarms the making circuit of starter coil 106. The closing of contact 106a maintains the circuit through starter coil 106 after contact 143a has opened. The closing of contact 106b energizes relay coil 107 to close contacts 107a, 107b and 107d, and to open contact 107c. The opening of contact 107c partially disarms the boom "up" circuit. The closing of contact 107a maintains the circuit through relay coil 107 after contact 106b has opened. The closing of contact 107b partially arms the boom "down" circuit. The closing of contact 107d arms the making circuit for "clamp" relay coil 114.

As the discharger moves away from its "out" position, limit switch 149 attached to track 50 is actuated by switch cam 163 mounted on carriage 49, to close contacts 149a and 149b. The closing of contact 149a arms the circuit for discharger "reverse" starter coil 109. The closing of contact 149b energizes relay coil 141 to close contact 141a and open contact 141b. The opening of contact 141b partially disarms the boom "down" circuit. The closing of contact 141a starts the time clock on its timing interval, opening clock contact 99a and closing clock contact 99b. The opening of contact 99a extinguishes red signal light 146. The closing of contact 99b energizes relay coil 144 to close contact 144a and open contact 144b. The closing of contact 144a lights green signal light 145. The opening of contact 144b disarms the making circuit of relay coil 143.

When the discharge boom has moved into the furnace the required distance to properly index the boom jaws above the billet about to be discharged, the forward motion of the discharge carriage is stopped by limit switch 147 which is mounted on carriage track 50 for operative engagement with switch cam 161 mounted on carriage 49. The opening of contact 147b de-energizes starter coil 106 to stop the forward movement of the discharge carriage. The de-energizing of starter coil 106 opens interlock contacts 106a and 106b, and closes interlock contacts 106c, 106d and 106e. The opening of contact 106a disarms the holding circuit of starter coil 106. The opening of contact 106b disarms the making circuit of relay coil 107. The closing of contact 106e arms the circuit of "reverse" starter coil 109. The closing of contact 106d arms the holding circuit of hearth starting relay coil 137. The closing of contact 106e arms the holding circuit

of relay coils 142 and 143. The closing of contact 147a energizes relay coil 111 to close contact 111a and open contact 111b. The opening of contact 111b disarms the boom "up" circuit for safety purposes. The closing of contact 111a energizes solenoid valve "down" coil 101 to admit fluid to hydraulic cylinder 62 for lowering boom 55 to clamping level.

As the boom leaves its "up" position, limit switch 151 attached to carriage 49 is actuated by switch cam 166 attached to connecting rod 60. The opening of contact 151a de-energizes relay coil 112 to open contacts 112a and 112b and close contact 112c. The opening of contacts 112a and 112b disarms the discharge carriage starting circuits for purposes of safety. The closing of contact 112c arms the circuit for time delay relay coil 116. The closing of contact 151b arms the boom "up" circuit. When the boom reaches its "down" position, limit switch 150 attached to carriage 49 is actuated by switch cam 166 attached to connecting rod 60. The opening of contact 150b de-energizes relay coil 111, opening contact 111a and closing contact 111b. The opening of contact 111a de-energizes solenoid valve "down" coil 101. The closing of contact 111b arms the boom "up" circuit. The closing of contact 150a energizes relay coil 110 to close contacts 110a and 110b. The closing of contact 110b serves no purpose during this movement. The closing of contact 110a energizes relay coil 114 to close contacts 114a, 114b, 114c, 114d, 114e and 114g, and to open contact 114f. The closing of contacts 114a, 114b and 114c sets up their respective circuits for subsequent movements.

Contact 114d serves as an interlock to maintain the circuit through relay coil 114 after its making circuit has opened. The opening of contact 114f de-energizes relay coil 115 to open contacts 115a, 115b, 115c, 115d and 115e, and to close contact 115f. The opening of contact 115a disarms "forward" starter coil 106. The opening of contact 115b de-energizes relay coil 107 to open contacts 107a, 107b and 107d, and to close contact 107c. The opening of contact 107a disarms the holding circuit of relay coil 107. The opening of contact 107b partially disarms the boom "down" circuit. The closing of contact 107c partially arms the boom "up" circuit. The opening of contact 107d disarms the making circuit of "clamp" relay coil 114. The opening of contact 115c partially disarms the boom "up" circuit. The opening of contact 115d disarms the holding circuit of "unclamp" relay coil 115. The closing of contact 115f arms the holding circuit of "clamp" relay coil 114. The opening of contact 115e de-energizes solenoid valve "unclamp" coil 104. The closing of contact 114e energizes solenoid valve "clamp" coil 103 to admit fluid to hydraulic cylinder 65 to close the boom jaws.

As the boom jaws start to close, limit switch 152 attached to carriage 49 is actuated by switch cam 165 attached to movable jaw 55b to open contact 152a and partially disarm the boom "up" circuit. The closing of contact 114g energizes adjustable time delay relay coil 116 to close contact 116a after sufficient time has elapsed to permit the boom jaws to close and grip the billet. The closing of contact 116a energizes relay coil 113 to close contact 113a and open contact 113b. The opening of contact 113b disarms the boom "down" circuit for purposes of safety. The closing of contact 113a energizes solenoid valve "up" coil 102 to raise the boom. As the boom leaves its "down" position, limit switch 150 is actuated to

open contact 150a and close contact 150b. The opening of contact 150a de-energizes relay coil 110 to open contacts 110a and 110b. The opening of contact 110a disarms the making circuit of "clamp" relay coil 114. The opening of contact 110b disarms the making circuit of "unclamp" relay coil 115. The closing of contact 150b arms the boom "down" circuit. When the boom reaches its "up" position, limit switch 151 is actuated by switch cam 166 to close contact 151a and open contact 151b. The opening of contact 151b de-energizes relay coil 113 to open contact 113a and close contact 113b. The opening of contact 113a de-energizes solenoid valve boom "up" coil 102. The closing of contact 113b arms the boom "down" circuit. The closing of contact 111a energizes relay coil 112 to close contacts 112a and 112b and open contact 112c. The opening of contact 112c de-energizes time delay relay coil 116. The closing of contact 112a serves no purpose during this movement. The closing of contact 112b energizes "reverse" starter coil 109 of motor 51 to set discharge carriage 49 in motion away from the furnace.

The energizing of starter coil 109 opens interlock contact 109a and closes interlock contact 109b. The opening of contact 109a disarms "forward" starter coil 106 for purposes of safety. The closing of contact 109b energizes relay coil 108 to close contacts 108a, 108b and 108d, and to open contact 108c. The closing of contact 108a maintains the circuit through relay coil 108 after contact 109b has opened. The closing of contact 108b partially arms the boom "down" circuit. The closing of contact 108d arms the making circuit for "unclamp" relay coil 115. The opening of contact 108c serves no purpose during this movement.

The initial outward movement of the discharge carriage actuates limit switch 147 to open contact 147a and close contact 147b. The opening of contact 147a partially disarms the boom "down" circuit. The closing of contact 147b arms the discharger "forward" starting circuit.

When the discharge carriage reaches its "out" position, limit switch 149 is actuated to open contacts 149a and 149b. The opening of contact 149a de-energizes "reverse" starter coil 109 to stop the carriage. The de-energizing of starter coil 109 closes interlock contact 109a and opens interlock contact 109b. The closing of contact 109a arms the discharger "forward" starter circuit. The opening of contact 109b disarms the making circuit of relay coil 108.

The opening of contact 149b de-energizes relay coil 141 to open contact 141a and close contact 141b. The opening of contact 141a clears the time clock circuits and places its controls in readiness for inauguration of the succeeding discharge operation upon completion of its timing interval. The closing of contact 141b energizes relay coil 111 to close contact 111a and open contact 111b. The opening of contact 111b disarms the boom "up" circuit for safety purposes. The closing of contact 111a energizes solenoid valve "down" coil 101 to lower the boom.

The initial downward movement of the boom actuates limit switch 151 to open contact 151a and close contact 151b. The opening of contact 151a de-energizes relay coil 112 to open contacts 112a and 112b, and close contact 112c. The opening of contacts 112a and 112b disarms the discharge carriage starting circuits for purposes of safety. The closing of contact 112c serves no purpose during this movement. The closing of

contact 151b arms the boom "up" circuit. When the boom arrives at its "down" position, limit switch 150 is actuated to close contact 150a and open contact 150b. The opening of contact 150b de-energizes relay coil 111 to open contact 111a and close contact 111b. The opening of contact 111a de-energizes solenoid valve "down" coil 101. The closing of contact 111b arms the boom "up" circuit. The closing of contact 150a energizes relay coil 110 to close contacts 110a and 110b. Contact 110a serves no purpose during this movement. The closing of contact 110b energizes relay coil 115 to close contacts 115a, 115b, 115c, 115d and 115e, and to open contact 115f. The closing of contacts 115a, 115b and 115c sets up their respective circuits for subsequent movements. The closing of contact 115d provides an interlock to maintain the circuit through relay coil 115 after its making circuit has opened. The opening of contact 115f de-energizes relay coil 114 to open contacts 114a, 114b, 114c, 114d, 114e and 114g, and to close contact 114f. The opening of contact 114a de-energizes relay coil 108 to open contacts 108a, 108b and 108d, and to close contact 108c. The opening of contact 108a disarms the holding circuit of relay coil 108. The opening of contact 108b partially disarms the boom "down" circuit. The opening of contact 108d disarms the making circuit of "unclamp" relay coil 115. The closing of contact 108c partially arms the boom "up" circuit. The opening of contact 114b disarms "reverse" starter coil 109. The opening of contact 114c partially disarms the boom "up" circuit. The opening of contact 114d disarms the holding circuit of "clamp" relay coil 114. The opening of contact 114e de-energizes solenoid valve "clamp" coil 103. The opening of contact 114g serves no purpose during this movement. The closing of contact 114f arms the holding circuit of "unclamp" relay coil 115. The closing of contact 115e energizes solenoid valve "unclamp" coil 104 to open the boom jaws and release the hot billet for delivery to the piercing mill by auxiliary conveying means which is not a component of this invention.

At the end of the "unclamp" stroke of hydraulic cylinder 65, limit switch 152 mounted on carriage 49 is actuated by switch cam 165 attached to movable jaw 55b. The closing of contact 152a energizes relay coil 113, closing contact 113a and opening contact 113b. The opening of contact 113b disarms the boom "down" circuit for purposes of safety. The closing of contact 113a energizes solenoid valve "up" coil 102 to raise the boom. As the boom leaves its "down" position, limit switch 150 is actuated to open contact 150a and close contact 150b. The opening of contact 150a de-energizes relay coil 110 to open contacts 110a and 110b. The opening of contact 110a disarms the making circuit of "clamp" relay coil 114. The opening of contact 110b disarms the making circuit of "unclamp" relay coil 115. The closing of contact 150b arms the boom "down" circuit. When the boom arrives at the "up" position, limit switch 151 is actuated to close contact 151a and open contact 151b. The opening of contact 151b de-energizes relay coil 113 to open contact 113a and close contact 113b. The opening of contact 113a de-energizes solenoid valve boom "up" coil 102. The closing of contact 113b arms the boom "down" circuit. The closing of contact 151a energizes relay coil 112, closing contacts 112a and 112b, and opening contact 112c. The closing of contact 112b and the opening of contact 112c serve no purpose during this move-

ment. The closing of contact 112a arms the circuit through starter coil 106, thus completing one sequence of movements by the discharge machine and placing the controls in readiness for inauguration of the succeeding discharge operation when signalled by the time clock.

The hearth now moves forward and stops at the next succeeding station. Depending on the spacing of the billets on the hearth, this may be a charging station, a discharge station or a station at which both charging and discharging occur.

With the sequence controller set for charging and discharging on the same hearth spacing, the charger and discharger both function at each stop. When operating in this manner, the hearth is started by the discharger and stopped by the sequence controller as hereinafter described.

With the sequence controller set for operation on unequal stations, the hearth is started by either the charger or the discharger and stopped by the sequence controller at the next succeeding station to move into index for either charging or discharging. It is to be noted that during operation on unequal hearth spacing, at periodic intervals a charging station and a discharge station will move into index concurrently. When this occurs, the sequence controller functions as though it were set for equal stations and the next succeeding movement of the hearth is initiated by the discharger. For example, if the charging spacing is double the discharge spacing, the charger and discharger function concurrently at each alternate stop and the discharger functions alone at the intermediate stop. For hearth spacings involving fractional ratios such as 5 to 3, a charging station and a discharge station move into index concurrently at each seventh stop of the hearth and the six intermediate stations move into index non-concurrently.

When the hearth is stopped by the sequence controller at a non-concurrent station for charging, the succeeding hearth movement is initiated by the charger, the starting impulse being supplied by "one-way" limit switch 154, which is actuated by switch cam 162 after the charger has delivered its cold billet and has started to move away from the furnace. The actuation of limit switch 154 momentarily closes contact 154a and momentarily opens contact 154b. The opening of contact 154b de-energizes relay coil 133 to open contacts 133a and 133b. The opening of contact 133a disarms charger "forward" starter coil 122. The opening of contact 133b disarms the maintaining circuit for relay coil 133. The closing of contact 154a energizes time delay relay coil 139 to close contacts 139a and 139b. The closing of contact 139b maintains the circuit through relay coil 139 after contact 154a has opened. The closing of contact 139a energizes starter coil 135 to set the hearth in motion. As the hearth starts to move, contact 97a of the sequence controller closes, and energizes relay coil 140 to close contacts 140b, 140c and 140d, and to open contacts 140a and 140e. The opening of contact 140a disarms charger "forward" starter coil 122. The closing of contact 140b energizes relay coil 133 to close contacts 133a and 133b. The closing of contact 133a arms charger "forward" starter coil 122. The closing of contact 133b maintains the circuit through relay coil 133 after contact 140b has opened. The closing of contact 140c arms the "discharger actuated" making circuit for hearth starter coil 135. The closing of contact 140d completes the holding

circuit for continuing the hearth in motion after contact 139a has opened. The opening of contact 140e de-energizes time delay relay coil 139 to open contacts 139a and 139b. The opening of contact 139b disarms the holding circuit of time delay relay coil 139. The opening of contact 139a disarms the "charger actuated" making circuit for hearth starter coil 135. The opening of contact 139a is momentarily delayed to insure that the holding circuit is completed by the closing of contact 140d before the making circuit is interrupted. The hearth continues in motion until it is stopped by the sequence controller at the next succeeding station in the manner hereinafter described.

When the hearth is stopped by the sequence controller at a non-concurrent station for discharging, the succeeding hearth movement is initiated by the discharger, the starting impulse being supplied by "one-way" limit switch 148 which is actuated by switch cam 167 after the discharger picks up its hot billet and has started to move away from the furnace. The actuation of limit switch 148 momentarily closes contact 148a to energize time delay relay coil 137 to close contacts 137a, 137b and 137c. The closing of contact 137b maintains the holding circuit through relay coil 137 after its making circuit has opened. The closing of contact 137c serves no purpose during this movement. The closing of contact 137a energizes starter coil 135 to set the hearth in motion. As the hearth starts to move, contact 98a of the sequence controller closes and energizes relay coil 138 to open contacts 138a and 138d, and close contacts 138b and 138c. The opening of contact 138a disarms discharger "forward" starter coil 106. The closing of contact 138b arms the "charger actuated" making circuit for hearth starter coil 135. The closing of contact 138c completes the holding circuit for continuing the hearth in motion after contact 137a of the making circuit has opened. The opening of contact 138d deenergizes time delay relay coil 137 to open contacts 137a, 137b and 137c. The opening of contact 137b disarms the holding circuit of time delay relay coil 137. The opening of contact 137c serves no purpose during this movement. The opening of contact 137a disarms the "discharger actuated" making circuit for hearth starter coil 105. The opening of contact 137a is momentarily delayed to insure that the holding circuit is completed by the closing of contact 138c before the making circuit is interrupted. The hearth continues in motion until it is stopped by the sequence controller at the next succeeding station in the manner hereinafter described.

When the hearth is stopped by the sequence controller at a concurrent station for charging and discharging, the succeeding hearth movement is initiated by the discharger. This applies whether the sequence controller is set for operation on equal stations as shown in Fig. 10 or on unequal stations as shown in Fig. 2. When the hearth stops at a concurrent station, the charger starts immediately and normally completes its function ahead of the discharger which must await its signal from the time clock. It is therefore essential to defer starting the hearth until the outgoing hot billet has been gripped by the discharger boom jaws and lifted clear of the hearth. In the accomplishment of this result, the sequence controller and its auxiliary controls function in the following manner. When the hearth arrives at a concurrent station, pawls

75 and 76 fall simultaneously into the engaging notches of their respective cam discs. Contacts 97a and 98a are thus opened simultaneously to de-energize relay coils 138 and 140, opening contacts 138b, 138c, 140b, 140c and 140d, and closing contacts 138a, 138d, 140a and 140e. The opening of contacts 138c and 140d de-energizes starter coil 135 and stops the hearth. The opening of contact 140c disarms the "discharger actuated" hearth starting circuit. The opening of contact 138b disarms the "charger actuated" hearth starting circuit. The opening of contact 140b and the closing of contact 140e serve no purpose during this movement. The closing of contact 138d arms the holding circuit for relay coil 137. The closing of contact 140a sets the charger in motion but the closing of contact 154a during its outward travel does not start the hearth as previously described in respect to non-concurrent operation because contact 138b of the "charger actuated" hearth starting circuit is open.

Upon termination of the timing interval, the discharger is set in motion by the time clock and a discharge operation is completed in the manner previously described. When the discharger has picked up its hot billet and has started to move away from the furnace, limit switch 148 is actuated to momentarily close contact 148a. The closing of contact 148a energizes time delay relay coil 137 to close contacts 137a, 137b and 137c. The closing of contact 137a arms the "discharger actuated" making circuit of hearth starter coil 135. The closing of contact 137b maintains the holding circuit through time delay relay coil 137 after its making circuit has opened. The closing of contact 137c energizes relay coil 140 to open contacts 140a and 140e, and to close contacts 140b, 140c and 140d. The opening of contact 140a disarms the charger "forward" starting circuit. The closing of contact 140b energizes relay coil 133 to close contacts 133a and 133b. The closing of contact 133a arms charger "forward" starter coil 122. The closing of contact 133b maintains the circuit through relay coil 133 after contact 140b has opened. The closing of contact 140d arms the holding circuit for hearth starter coil 135. The opening of contact 140e disarms the holding circuit for time delay relay coil 139. The closing of contact 140c energizes starter coil 135 to set the hearth in motion.

As the hearth starts to move, contact 98a of the sequence controller closes and energizes relay coil 138 to open contacts 138a and 138d, and close contacts 138b and 138c. The opening of contact 138a disarms the discharger "forward" starting circuit. The closing of contact 138b arms the "charger actuated" making circuit for hearth starter coil 135. The closing of contact 138c completes the holding circuit for continuing the hearth in motion after contact 137a of the making circuit has opened. The opening of contact 138d de-energizes time delay relay coil 137 to open contacts 137a, 137b and 137c. The opening of contact 137b disarms the holding circuit for time delay relay coil 137. The opening of contact 137c serves no purpose during this movement. The opening of contact 137a disarms the "discharger actuated" making circuit for hearth starter coil 135. The opening of contact 137a is momentarily delayed to insure that the holding circuit is completed by the closing of contact 138c before the making circuit is interrupted.

The hearth continues in motion until it is stopped by the sequence controller at the next succeeding station in the manner hereinafter described.

- 5 Irrespective of whether the hearth has been set in motion by the charger or discharger as previously described, it is stopped by the sequence controller in proper index at the next succeeding station, which may be a non-concurrent charging station, a non-concurrent discharge station or a concurrent station for both charging and discharging.

When the sequence controller presents a "non-concurrent" notch in cam cylinder 74 into which its mating pawl 76 can fall, the hearth is stopped at a discharge station by the opening of contact 98a which de-energizes relay coil 138 to open contacts 138b and 138c, and to close contacts 138a and 138d. The opening of contact 138b disarms the "charger actuated" making circuit for hearth starter coil 135. The closing of contact 138d arms the holding circuit for time delay relay coil 137. The opening of contact 138c de-energizes starter coil 135 and stops the hearth. The closing of contact 138a arms the discharger "forward" starting circuit, thus placing the controls in readiness for the discharge operation to follow upon signal by the time clock.

When the sequence controller presents a non-concurrent notch in cam cylinder 73 into which its mating pawl 75 can fall, the hearth is stopped at a charging station by the opening of contact 97a which de-energizes relay coil 140 to close contacts 140a and 140e, and to open contacts 140b, 140d and 140c. The closing of contact 140e arms the holding circuit for time delay relay coil 139. The opening of contact 140b disarms the making circuit for relay coil 133. The opening of contact 140c disarms the "discharger actuated" making circuit for hearth starter coil 135. The closing of contact 140a energizes starter coil 122 to initiate a cycle of operation by the charger as hereinafter described.

When the sequence controller concurrently presents a charging notch and a discharge notch into which pawls 75 and 76 can fall, contacts 97a and 98a are opened simultaneously to de-energize relay coils 138 and 140, thus opening contacts 138b, 138c, 140b, 140c and 140d, and closing contacts 138a, 138d, 140a and 140e. The opening of contacts 138c and 140d de-energizes starter coil 135 to stop the hearth. The closing of contact 138a arms the discharger "forward" starter circuit for subsequent initiation of the discharge operation by the time clock. The closing of contact 140a energizes charger "forward" starter coil 122 to initiate a cycle of operation by the charger as hereinafter described. The balance of the contacts affected by the de-energizing of relay coils 138 and 140 function the same as at non-concurrent hearth stops as previously described.

When the hearth stops at a charging station, either concurrent or non-concurrent, the sequence controller functions as previously described to set the charger in motion by the closing of contact 148a. The ensuing sequence of movements by the functional components of the charger are attained in the following manner.

The closing of contact 148a energizes starter coil 122 to start motor 28 and set the charger in motion toward the furnace. As the charger moves away from the "out" position, limit switch 155 attached to track 27 is actuated by switch cam 163 attached to carriage 26. The opening of contact 155a partially disarms the boom

"down" circuit. The closing of contact 155b arms the charger "reverse" starter circuit. The energizing of starter coil 122 closes interlock contact 122a and opens interlock contacts 122b and 122c. The opening of contact 122b disarms the charger "reverse" starter circuit for purposes of safety. The opening of contact 122c disarms the holding circuit of hearth starting relay coil 139. The closing of contact 122a energizes relay coil 124 to close contacts 124a, 124b and 124d, and to open contact 124c. The closing of contact 124a maintains the circuit through relay coil 124 after contact 122a has opened. The closing of contact 124b partially arms the boom "down" circuit. The opening of contact 124c partially disarms boom "up" circuit. The closing of contact 124d arms the making circuit for "unclamp" relay coil 130.

When the charger has moved forward to properly position its cold billet above the hearth, limit switch 153 attached to track 27 is actuated by switch cam 162 attached to carriage 26. The opening of contact 153b de-energizes starter coil 122 to stop the charger. The closing of contact 153a energizes relay coil 127, closing contact 127a and opening contact 127b. The opening of contact 127b disarms the boom "up" circuit for safety purposes. The closing of contact 127a energizes solenoid "down" coil 117 to admit fluid to hydraulic cylinder 39 for lowering boom 32 to unclamping level. As the boom leaves its "up" position, limit switch 157 attached to carriage 26 is actuated by switch cam 160 attached to connecting rod 37. The closing of contact 157b arms the boom "up" circuit. The opening of contact 157a de-energizes relay coil 128 to open contacts 128a and 128b and close contact 128c. The opening of contacts 128a and 128b disarms the charger starter circuits for purposes of safety. The closing of contact 128c serves no purpose during this movement.

When the boom reaches its "down" position, limit switch 155 attached to carriage 26 is actuated by switch cam 160 attached to connecting rod 37. The opening of contact 155b de-energizes relay coil 127 to open contact 127a and close contact 127b. The opening of contact 127a de-energizes boom "down" solenoid valve coil 117. The closing of contact 127b arms the boom "up" circuit. The closing of contact 156a energizes relay coil 126 to close contacts 126a and 126b. The closing of contact 126b serves no purpose during this movement. The closing of contact 126a energizes relay coil 130 to close contacts 130a, 130b, 130c, 130d and 130f, and to open contact 130e. The closing of contacts 130a, 130b and 130f sets up their respective circuits for subsequent movements. Contact 130d serves as an interlock to maintain the circuit through relay coil 130 after its making circuit has opened. The opening of contact 130a de-energizes relay coil 131 to open contacts 131a, 131b, 131c, 131d, 131f and 131g, and to close contact 131a. The opening of contacts 131a, 131b and 131d sets up their respective circuits for subsequent movements. The opening of contact 131f disarms the holding circuit of relay coil 131. The opening of contact 131g serves no purpose during this movement. The closing of contact 131a completes the holding circuit for relay coil 130. The opening of contact 131c de-energizes solenoid valve "clamp" coil 120. The closing of contact 130c energizes solenoid valve "unclamp" coil 119 to admit fluid to hydraulic cylinder 42 to open the

boom jaws and deposit the cold billet on the hearth.

As the boom jaws arrive at the "open" position, limit switch 158 attached to carriage 26 is actuated by switch cam 161 attached to boom jaw 32b, thus closing contact 158a and energizing relay coil 129 to close contact 129a and open contact 129b. The opening of contact 129b disarms the boom "down" circuit for safety purposes. The closing of contact 129a energizes solenoid valve "up" coil 118 to admit fluid to hydraulic cylinder 39 for raising the boom. As the boom leaves its "down" position, limit switch 156 is actuated to open contact 156a and close contact 156b. The closing of contact 156b arms the boom "down" circuit. The opening of contact 156a de-energizes relay coil 126 to open contacts 126a and 126b. The opening of contact 126a serves no purpose during this movement. The opening of contact 126b partially disarms the "clamp" relay circuit. As the boom arrives at its "up" position, limit switch 157 is actuated by switch cam 160 to close contact 157a and open contact 157b. The opening of contact 157b de-energizes relay coil 129 to open contact 129a and close contact 129b. The opening of contact 129a de-energizes boom "up" solenoid valve coil 118. The closing of contact 129b arms the boom "down" circuit. The closing of contact 157a energizes relay coil 128 to close contacts 128a and 128b and open contact 128c. The closing of contact 128a serves no purpose during this movement. The opening of contact 128c disarms time delay relay coil 132. The closing of contact 128b energizes "reverse" starter coil 125 of motor 28 to set the charger carriage in motion away from the furnace. As the charger moves away from its "in" position, limit switch 153 is actuated to open contact 153a and close contact 153b. The opening of contact 153a partially disarms the boom "down" circuit. The closing of contact 153b arms the charger "in" starter circuit.

The energizing of starter coil 125 opens interlock contact 125a and closes interlock contact 125b. The opening of contact 125a disarms "forward" starter coil 122 for safety purposes. The closing of contact 125b energizes relay coil 123 to close contacts 123a, 123b and 123d, and to open contact 123c. The closing of contact 123a maintains the circuit through relay coil 123 after contact 125b has opened. The closing of contact 123b partially arms the boom "down" circuit. The opening of contact 123c partially disarms the boom "up" circuit. The closing of contact 123d partially arms the "clamp" relay circuit. When the charger carriage reaches its "out" position, limit switch 155 is actuated to close contact 155a and open contact 155b. The opening of contact 155b de-energizes reverse starter coil 125 to stop the carriage in the "out" position. The closing of contact 155a energizes relay coil 127 to close contact 127a and open contact 127b. The opening of contact 127b disarms the boom "up" circuit. The closing of contact 127a energizes solenoid valve "down" coil 117 to lower the boom to clamping level.

As the boom leaves its "up" position, limit switch 157 is actuated to open contact 157a and close contact 157b. The closing of contact 157b arms the boom "up" circuit. The opening of contact 157a de-energizes relay coil 128 to open contacts 128a and 128b, and to close contact 128c. The opening of contacts 128a and 128b disarms the charging starter circuits for purposes

of safety. The closing of contact 128c arms the circuit for time delay relay coil 132.

When the boom reaches its "down" position, limit switch 156 is actuated to close contact 156a and open contact 156b. The opening of contact 156b de-energizes relay coil 127 to open contact 127a and close contact 127b. The opening of contact 127a de-energizes boom "down" solenoid valve coil 117. The closing of contact 127b arms the boom "up" circuit. The closing of contact 156a energizes relay coil 126 to close contacts 126a and 126b. The closing of contact 126a serves no purpose during this movement. The closing of contact 126b energizes relay coil 131 to close contacts 131a, 131b, 131c, 131d, 131f and 131g, and to open contact 131e. The closing of contacts 131a, 131b and 131d sets up their respective circuits for subsequent movements. Contact 131f serves as an interlock to maintain the circuit through relay coil 131 after its making circuit has opened. The opening of contact 131e de-energizes relay coil 130 to open contacts 130a, 130b, 130c, 130d and 130f, and to close contact 130e. The opening of contact 130b disarms the charger "reverse" starting circuit. The opening of contact 130c de-energizes solenoid valve "unclamp" coil 119. The opening of contact 130d disarms the holding circuit for "unclamp" relay coil 130. The closing of contact 130e arms the holding circuit for "clamp" relay coil 131. The opening of contact 130f partially disarms the boom "up" circuit. The opening of contact 130a de-energizes relay coil 123 to open contacts 123a, 123b and 123d, and to close contact 123c. The opening of contact 123a disarms the holding circuit for relay coil 123. The opening of contact 123b partially disarms the boom "down" circuit. The closing of contact 123c partially arms the boom "up" circuit. The opening of contact 123d disarms the making circuit for "clamp" relay coil 131. The closing of contact 123e energizes solenoid valve "clamp" coil 120 to admit fluid to hydraulic cylinder 42 for closing the boom jaws to clamp a previously positioned cold billet for the next succeeding charging operation.

Various means for moving the incoming cold billets successively into clamping position are well known to those skilled in the art and are not included as a component of this invention. Flag switch 159 is employed as a safety feature to prevent any possible conflict of movements in respect to the incoming cold billet and the boom jaws. When the cold billet has moved into clamping position, flag switch 159 is actuated by the billet to close contact 159a and thus arm the boom "down" circuit for lowering the boom by the closing of contact 155a as previously described. In case the movement of the billet into clamping position is delayed, the closing of contact 155a arms the boom "down" circuit and the subsequent movement of the cold billet into clamping position closes contact 159a and lowers the boom.

The closing of contact 131g energizes adjustable time delay relay coil 132 to close contact 132a after sufficient time has elapsed for the boom jaws to close and grip the billet. The closing of contact 132a energizes relay coil 129 to close contact 129a and open contact 129b. The opening of contact 129b disarms the boom "down" circuit for purposes of safety. The closing of contact 129a energizes solenoid valve "up" coil 118, admitting fluid to hydraulic cylinder 39 to raise the boom and its clamped cold billet to the "up" position. As the boom leaves its "down" posi-

tion, limit switch 156 is actuated to open contact 156a and close contact 156b. The closing of contact 156b arms the boom "down" circuit. The opening of contact 156a de-energizes relay coil 126 to open contacts 126a and 126b. The opening of contact 126a disarms the making circuit for "unclamp" relay coil 130. The opening of contact 126b serves no purpose during this movement. As the boom arrives at the "up" position, limit switch 157 is actuated to close contact 157a and open contact 157b. The opening of contact 157b de-energizes relay coil 129 to open contact 129a and close contact 129b. The opening of contact 129a de-energizes boom "up" solenoid valve coil 118. The closing of contact 129b arms the boom "down" circuit. The closing of contact 157a energizes relay coil 128 to close contacts 128a and 128b, and to open contact 128c. The opening of contact 128c de-energizes time delay relay coil 132. The closing of contact 128b serves no purpose during this movement. The closing of contact 128a arms the "forward" starting circuit of charger motor 28, thus completing one cycle of operation by the charger and placing its control circuits in readiness for initiation of the subsequent charging cycle upon signal from the sequence controller.

For purposes of clarity, the plurality of movements involved in the functioning of the invention are hereinbefore described as occurring separately. In actual practice, each signal by the time clock initiates a sequence of movements which continue without interruption until all of the movements required to satisfy the existing loading pattern have been completed. In each case the sequence begins when the discharger is set in motion by the time clock and ends when the next succeeding hot billet moves into index with the discharge door. The intervening movements are fixed by the loading pattern and consummated by the sequence controller. In "concurrent" operation as portrayed by Fig. 10, the sequence is comprised of one movement each by the charger, discharger and hearth, and is completed at each stop of the hearth. In "non-concurrent" operation as portrayed by Fig. 2, if the charging spacing is less than the discharge spacing, the charger and the hearth may execute two or more intervening movements before the succeeding hot billet moves into discharge index to complete the sequence. Or conversely, if the charging spacing is larger than the discharge spacing, the sequence may be completed without any intervening movements by the charger.

All of the foregoing operating sequences are automatically attained by the controls as illustrated and described. The only manual adjustment involved is the setting of the sequence controller to the required hearth spacing.

While I have described my invention as embodied in concrete form and as operating in a specific manner in accordance with the provision of the patent statutes, it is to be understood that I do not limit my invention thereto, since various modifications thereof will suggest themselves to those skilled in the art without departing from the spirit of the invention.

I claim:

1. In a rotary hearth furnace, a rotatable hearth, a drive mechanism for rotating said hearth to advance said hearth in steps of predetermined distances, charging mechanism for delivering articles to be heated into the furnace chamber and depositing the same on said hearth, discharging mechanism for removing the heated

articles from said hearth and withdrawing the same from the furnace chamber, and a selector mechanism for coordinating the movements of the charging and discharging mechanisms independently of each other with different step-by-step movements of the hearth.

2. In a rotary hearth furnace, a rotatable hearth, a drive mechanism for rotating said hearth including an electric motor, a selector mechanism operable in response to rotary movement of the hearth for stopping the hearth movement at predetermined distances of hearth travel, charging mechanism for loading articles to be heated on said hearth, discharging mechanism for unloading the heated articles from said hearth, electrically energized operating mechanisms for the charging and discharging mechanisms including a time clock controlling the operation of said discharging mechanism, and means operable by said discharging mechanism for energizing the hearth drive mechanism.

3. In a rotary hearth furnace, a rotatable hearth, a drive mechanism for rotating said hearth including an electric motor, a selector mechanism operable in response to rotary movement of the hearth for stopping the hearth movement at predetermined distances of hearth travel, charging mechanism for loading articles to be heated on said hearth, discharging mechanism for unloading the heated articles from said hearth, electrically energized operating mechanisms for the charging and discharging mechanisms including a time clock controlling the operation of said discharging mechanism, means operable by said discharging mechanism for energizing the hearth drive mechanism, and means operable by said selector mechanism for energizing said charging operating mechanism.

4. In combination, a movable conveyor, a charging mechanism for loading articles on said conveyor, a discharge mechanism for unloading said conveyor, drive means for said conveyor, operating mechanisms for said charging and discharging mechanisms, means operable in response to movement of said conveyor for integrating the conveyor movements into predetermined station stops for both the loading and unloading of articles from said conveyor independently of each other, a time clock controlling the operation of said discharge mechanism, and means operable by said discharge mechanism for energizing said conveyor drive mechanism.

5. In a rotary hearth furnace, a rotatable hearth, a drive mechanism for rotating said hearth including an electric motor, a selector mechanism operable in response to rotary movement of the hearth for stopping the hearth movement at predetermined distances of hearth travel, charging mechanism for loading articles to be heated on said hearth, discharging mechanism for unloading the heated articles from said hearth, electrically energized operating mechanisms for the charging and discharging mechanisms including a time clock controlling the operation of said discharging mechanism, and means operable by said discharging mechanism for energizing the hearth drive mechanism, said selector mechanism comprising a pair of cam cylinders, a counter-shaft for driving said cam cylinders operably connected to the hearth drive, a plurality of cam discs mounted on said cam cylinders, said discs being provided with angularly spaced notches, the number of notches of a particular disc determining the hearth spac-

ings for different station stops, cam pawls for engaging the notches in the cam discs for actuating a control switch for deenergizing the hearth drive motor when a pawl drops into a cam notch, said pawls being mounted to be adjustable over the full range of adjacent discs whereby the pawl cooperating with one row of discs of a cam cylinder may be adjusted to effect hearth spacings independently of the setting of the pawl on the other of said pair of cam cylinder discs.

6. In a rotary hearth furnace, a rotatable hearth, a drive mechanism for rotating said hearth including an electric motor, a selector mechanism for stopping the hearth movement at predetermined distances of hearth travel, charging mechanism for loading articles to be heated on said hearth, discharging mechanism for unloading the heated articles from said hearth, electrically energized operating mechanisms for the charging and discharging mechanisms including a time clock controlling the operation of said discharging mechanism, and means operable by said discharging mechanism for energizing the hearth drive mechanism, said selector mechanism comprising a pair of cam cylinders each consisting of a plurality of cam discs having angularly spaced notches, the notches in each disc of a row of discs varying in number in accordance with the range of hearth spacing desired, means for rotating said cam cylinders coordinately with the rotation of the furnace hearth, cam pawls for engaging the notches of the cam discs whereby the hearth drive motor is deenergized to stop the hearth, one of said cam cylinders functioning to integrate the hearth movements into predetermined station stops for loading the hearth, and the other of said cam cylinders being independently operable for integrating the hearth movements into predetermined station stops for unloading the articles from the hearth.

7. In a rotary hearth furnace for heating billets, a rotatable hearth, a drive mechanism for rotating said hearth, charging mechanism for loading billets with their axes disposed radially on the furnace hearth, discharging mechanism for unloading the billets in a radial line from the furnace hearth, selector mechanism for integrating the hearth movements into predetermined station stops for the charging and discharging mechanisms whereby the billets may be loaded on the hearth at different spacing than billets being unloaded from the hearth where such billets are of different sizes, a time clock controlling the rate of discharge of billets from the furnace, said time clock being adjustable to maintain a predetermined rate of production of billets of varying sizes.

8. In a rotary hearth furnace, a rotatable hearth, a drive mechanism for rotating said hearth including an electric motor, charging mechanism for loading articles to be heated on said hearth, discharging mechanism for unloading the heated articles from said hearth, a selector mechanism operable in response to rotary movement of the hearth for stopping the hearth movement at predetermined distances of hearth travel to receive a charge or for discharging, the selector mechanism being adjustable to stop the hearth at equal or unequal intervals for charging and discharging, and a time clock for controlling the rate of discharge of articles from the furnace in accordance with the varying sizes of such articles, means operable by the discharge

21

mechanism for energizing the hearth drive when the selector mechanism is set for equal spacing of the hearth for both the charge and discharge operations, and means operable by the charging mechanism for energizing the hearth drive mechanism when the selector mechanism is adjusted for unequal intervals of hearth movement between the charging and discharging stations.
